UNITED STATES PATENT OFFICE.

JOHN F. O'CONNOR, OF CHICAGO, ILLINOIS, ASSIGNOR TO WILLIAM H. MINER, OF CHICAGO, ILLINOIS.

FRICITION DRAFT-RIGGING FOR RAILWAY-CARS.

1,041,862.

Specification of Letters Patent.

Patented Oct. 22, 1912.

Application filed July 24, 1911. Serial No. 640,077.

To all whom it may concern:

Be it known that I, JOHN F. O'CONNOR, a citizen of the United States, residing in Chicago, in the county of Cook and State of Illinois, have invented a new and useful Improvement in Friction Draft-Rigging for Railway-Cars, of which the following is a specification.

My invention relates to friction draft rigging for railway cars.

The object of my invention is to provide a friction draft rigging of a simple, strong, safe, efficient and durable construction, having in addition to the ordinary yoke, front and rear followers and friction shell, a tandem arranged set of wedge members and friction shoes so arranged that the action on the first set of friction shoes is transmitted to the second wedge, which in turn operates on the second set of friction shoes or blocks, and a spring located between the wedge member to insure the return of the parts to their proper place after the buffing or pulling action ceases.

My invention consists in the novel parts and devices and in the novel combinations of parts and devices as herein shown, described and claimed.

In the drawings forming a part of this specification, Figure 1 is an elevation, partly in longitudinal, vertical section, showing the structure embodying my invention. Fig. 2 is a plan view of the same, partly in horizontal section. Fig. 3 is a transverse section taken substantially on the line 3—3 of Fig. 1, looking in the direction of the arrows, but showing the friction shoes in end elevation instead of in cross section. Fig. 4 is a transverse section of the friction cylinder and interior mechanism, taken on the line 4—4 of Fig. 1, looking in the direction of the arrows. Fig. 5 is an end elevation of the friction cylinder and the interior mechanism, taken at the left as viewed in Fig. 1. Fig. 6 is an end elevation of the outer or front wedge member. Fig. 7 is an interior view of one of the outer friction shoes or blocks. Fig. 8 is an end elevation of the inner wedge member and Fig. 9 is an in-

terior view of one of the inner friction shoes or blocks.

In the drawings 10, 10 represent the center sills between which is mounted the draft gearing. These center sills are provided with the usual front stops 11 and rear stops 12 against which the front and rear followers 13 and 14, respectively, are adapted to abut.

15 denotes the draw-bar and 16 the draft yoke rigidly attached thereto by means of 60 rivets 17, 17.

The gearing is supported between the center sills by means of a saddle 18 removably attached thereto by means of bolts 19.

Mounted between the followers is the longitudinally movable cylindrical friction shell 20, open at its front end, and provided with a rear end 21, said end or face 21 being further provided on the interior of the shell with a stepped spring centering lug 22 for the draft spring 23 and the follower spring 25. The rear face 21 is provided with a countersink 26, and passing through the lug 22 is a longitudinally extending headed bolt 27, having at one end thereof an adjusting nut 24 for maintaining the same within the shell and adjusting the initial tension of the springs. This bolt extends nearly to the front follower and has slidably mounted thereon at its front end the front or outer wedge member 28. This wedge member 28 preferably consists of a cylindrical outer portion 29, three wedge or inclined faces 30, and an inner bearing head 290. Loosely surrounding this wedge member 28 and confined within the friction shell 20 are three friction shoes or blocks 31, having exterior faces fitting the interior of the shell and each provided with an inner segmental cylindrical portion 32, coöoperating with the cylindrical part 29 of the wedge member 28. These blocks 31 are furthermore provided with inclined or wedging faces 33, coöoperating with the friction faces 30 of the wedge member or block 28. On the inner ends of the blocks 31 is a cylindrical portion 34, in which is adapted to be placed the restoring spring 35. This spring

35 is mounted on the rod 27 and abuts against the inner end or bearing head 290 of the wedge member 28 and the front end of the inner wedge member 36. This inner 5 wedge member 36 is somewhat similar in construction to the outer wedge member 28, having the cylindrical portion 37 and the inclined or wedging friction faces 38 corresponding respectively to the faces 29 and 10 30 of the front wedge member. Loosely surrounding this inner wedge member 36 are three friction shoes 39, loosely fitting within the shell 20 and having inner inclined or wedging faces 40, co-operating with the inclined faces 38 of the inner wedge member 36. On the inner end of each of these friction blocks 39 is a short cylindrical portion 41 within which is adapted to rest the end of the spring 25 also mounted on the rod 27, 15 and abutting at its inner end against the projection 22 formed on the end of the friction shell 20. The friction shell is maintained in its proper position within the yoke 16 by means of projections 42, as more 20 clearly shown in Fig. 5. Applicant, by the use of a restoring spring 35, located between the wedges 28 and 36, insures the positive 25 return of the wedges and friction shoes to their proper position upon removal of the 30 buffering or pulling action, and thus accomplishes a result which has been lacking in prior devices embodying a somewhat similar construction.

In operation, the wedge 28 first 35 presses the spring 35, which is of large capacity, and there is thus provided an initial resistance. Upon a continuation of the buffering or pulling action the shoes 31 are pressed into engagement with the shell and by their 40 inward movement engage the inner wedge 36 which in turn operates the friction shoes 39.

In the arrangement shown, applicant, by the use of one spring only, is able to more than double its effectiveness in resisting the 45 movement of the inner set of shoes by the tandem arrangement of the friction wedges.

I claim:-

1. In a friction draft rigging, the combination with a drawbar, draft yoke, center 50 sills, stops and followers, of a longitudinally movable friction shell, two friction wedges, a set of friction shoes coacting with each of said wedges, all arranged in tandem within the friction shell, a draft spring, and 55 a restoring spring between the wedges, substantially as specified.

2. In a friction draft rigging, the combination with a drawbar, draft yoke, center sills, stops and followers, of a longitudinally 60 movable friction shell having an inwardly extending lug on one end thereof, a longitudinally disposed rod extending within the shell and having slidably mounted thereon near its opposite end two similarly arranged

wedges, two sets of friction shoes having inclined internal wedging faces co-operating with said wedges and a spring on said rod between the wedge members, substantially as specified.

3. In a friction draft rigging, the combination with a drawbar, draft yoke, center sills, stops and followers, of a longitudinally movable friction shell, a draft spring therein, a set of circularly disposed inner friction shoes engaging said spring and each having inclined or wedging faces, a wedge interposed between said shoes, an outer set of friction shoes, the inner ends of which engage the outer end of the said wedge, said outer friction shoes each having inclined friction faces, a second wedge engaging the last named set of friction shoes, and a spring within the outer set of friction shoes, substantially as specified.

4. In a friction draft rigging, the combination with a drawbar, draft yoke, center sills, stops and followers, of a friction shell movable longitudinally, a longitudinally extending rod arranged therein, springs surrounding said rod, two wedges and a set of circularly arranged friction shoes co-acting with each of said wedges, each set having the corresponding friction faces thereof inclined in the same direction, and a restoring spring mounted on the rod between said wedges, substantially as specified.

5. In a friction draft rigging, the combination with a drawbar, draft yoke, center sills, stops and followers, of a longitudinally movable friction shell and springs therein, longitudinal, slidably mounted friction blocks circularly arranged within said shell near its outer end, each friction block having two segmental cylindrical inner surfaces connected by an intermediate inclined wedge 105 face, a wedge disposed within said blocks having faces co-operating with the inclined faces of the blocks, and an inner spring bearing end, a second set of friction blocks within the shell and each having inner inclined 110 friction faces engaged by a second wedge, each of said second named friction shoes having an inner segmental cylindrical portion for the reception of the end of one of the draft springs, and a restoring spring 115 engaging the bearing end of the outer wedge and the outer face of the second named wedge, substantially as specified.

6. In a draft rigging, a yoke, front and rear followers, a longitudinally movable cylindrical friction shell, two wedges arranged tandem within said shell and each slidably mounted on a rod extending throughout the length of the shell, a restoring spring on said rod between and engaging said wedges, outer 120 friction shoes surrounding the outer one of the wedges and engaging both wedges, inner friction shoes surrounding the inner one of

the wedges, and draft springs, substantially as specified.

7. In a friction draft rigging, a longitudinally movable friction shell, a pair of wedges, two sets of friction shoes, each set coöperating with one of the wedges, the wedges and sets of friction shoes having their corresponding coöperating friction

faces inclined in the same direction and arranged in tandem, a shock-absorbing spring, 10 and a restoring spring for releasing the friction shoes, substantially as specified.

JOHN F. O'CONNOR.
